(57) **CLAIM**

We claim the ornamental design for a digital video recorder, as shown and described.

DESCRIPTION

FIG. 1 is a perspective view of the design for a digital video recorder;

FIG. 2 is a front view of the design of FIG. 1;

FIG. 3 is a rear view of the design of FIG. 1;

FIG. 4 is a left side view of the design of FIG. 1;

FIG. 5 is a right side view of the design of FIG. 1;

FIG. 6 is a top view of the design of FIG. 1; and,

FIG. 7 is a bottom view of the design of FIG. 1.
